UNITED STATES PATENT OFFICE.

CHARLES G. BAITZ, OF NEW YORK, N. Y.

MOUNTING FOR DOLL HEADS ON WIRE FRAMES.

Application filed March 5, 1924. Serial No. 697,133.

To all whom it may concern:

Be it known that I, CHARLES G. BAITZ, a citizen of Rumania, residing in New York, in the county of New York and State 5 of New York, have invented a new and useful Mounting for Doll Heads on Wire Frames, of which the following is a specification.

The object of my invention is to provide 10 an improved mounting of the type herein- after described and disclosed in the accom- panying drawings. The article is used for boudoir lights, ornamental dolls, telephone concealers and the like. My main object 15 is to provide a novel method of attaching the head to the frame by screwing it on. Heretofore, wires have been used for at- taching the head or bust to the wire frames, which method has proved tedious and cum- 20 bersome.—

Figure 1 is a perspective view of my device;

Fig. 2 is a bottom plan view of the bust of the doll, and

Fig. 3 is a detailed vertical section of the mounting.

Like numerals indicate like parts in each of the several views.

Referring to the accompanying drawings, 30 1 designates the wire frame, to which is attached the novel hollow, circular, tapered mounting member 2, having a threaded upper end portion 3, adapted for screw- threaded engagement with the threaded 35 metal seat 4, preferably of the ring shape

shown in Fig. 3, positioned approximately in the center of the bust 5 of the doll. The frame 1 composes the doll body and is also a support for the bust for display purposes for a dress, which dress may conceal a telephone, or function as a shade for a boudoir lamp or the like.

This construction permits of unscrewing the bust from the frame for convenience in shipment, and also facilitates dressing the 45 doll. There is also an advantage in that there is less danger of injury to the doll than is the case with the former method of mounting, which consists of imbedding wires directly in the bust of the doll.

What I claim is:

1. In a mounting for doll heads on wire frames, the combination of a wire frame, a hollow tapered circular mounting member having a threaded upper end portion, a doll 55 bust, and a threaded seat extending upward into the lower portion of the aforesaid doll bust, and adapted for screw threaded engagement with the above mentioned circular mounting member.

2. In a mounting for doll heads on wire frames, the combination of a wire frame, a mounting member having a threaded upper end portion, a doll bust, and a threaded seat extending upward into the lower portion of the aforesaid doll bust and adapted for screw threaded engagement with the above mentioned circular mounting member.

CHARLES G. BAITZ.
